(57) **CLAIM**

The ornamental design for a fixture section with messaging hierarchy, as shown and described.

DESCRIPTION

FIG. 1 is a top right perspective view of a fixture section with a messaging hierarchy of the present invention;

FIG. 2 is a front side elevational view thereof;

FIG. 3 is a top plan view thereof; and,

FIG. 4 is a right side elevational view thereof, with the left side view being a mirror image thereof.

The evenly spaced broken lines shown in the drawings are directed to environment, for informational purposes only and form no part of the claimed design. The long evenly spaced broken lines that define the bounds of the claimed design form no part thereof.

The vertical lines on the claimed portion of the design are not surface treatment but are lining to indicate the item is opaque.
